FASTENER FOR SECURING TOGETHER LAYERS OF PAPERBOARD, ASBESTOS CLOTH AND SIMI- LAR MATERIALS

William J. Wheatley, Jr., Dresher, Pa., assignor to Phila-
delphia Asbestos Corporation, Philadelphia, Pa., a cor-
poration of Pennsylvania

Filed Aug. 19, 1968, Ser. No. 13,179

Term of patent 14 years

Int. Cl. D8—03

U.S. Cl. D9—252

FIG. 1

FIG. 2

FIG. 3

FIG. 4

FIG. 5

FIG. 6

FIGURE 1 is a perspective view of the fastener;
FIGURE 2 is a top plan view thereof;
FIGURE 3 is a bottom plan view thereof;
FIGURE 4 is a front elevational view thereof, showing
in broken lines a plurality of superposed fastened layers
for illustrative purposes only;

FIGURE 5 is a side elevational view thereof, showing
in broken lines a plurality of superposed fastened layers
for illustrative purposes only; and

FIGURE 6 is a perspective view of a modified form
of the fastener.

I claim:
The ornamental design for a fastener for securing to-
gether layers of paperboard, asbestos cloth and similar
materials, as shown and described.
